US00D656610S

(12) **United States Design Patent**
Kleiner

(10) **Patent No.:** **US D656,610 S**
(45) **Date of Patent:** **** Mar. 27, 2012**

(54) **SPINAL DISTRACTION INSTRUMENT**(76) Inventor: **Jeffrey B. Kleiner**, Denver, CO (US)(**) Term: **14 Years**(21) Appl. No.: **29/393,737**(22) Filed: **Jun. 8, 2011**

FIG. 1 is a front perspective view of a spinal distraction instrument showing my new design;
FIG. 2 is a rear perspective view thereof;
FIG. 3 is a front elevation view thereof;
FIG. 4 is a rear elevation view thereof;
FIG. 5 is a right elevation view thereof;
FIG. 6 is a left elevation view thereof;
FIG. 7 is a top plan view thereof; and,
FIG. 8 is a bottom plan view thereof.
